BUILDING PARTITION

Filed March 12, 1926

Inventor

FREDERICK M. VENZIE,

William J. Saeter
Attorney

UNITED STATES PATENT OFFICE

FREDERICK M. VENZIE, OF PHILADELPHIA, PENNSYLVANIA

BUILDING PARTITION

Application filed March 12, 1926. Serial No. 94,292.

The invention, generally stated, relates to building material and has more especial relation to partition structures such as walls, ceilings and the like.

5 The leading object of the present invention may be said to reside in the provision of a novel slab for building partition which is of simple, efficient and comparatively inexpensive structure; which is very light in weight 10 to facilitate easy handling in erection; which contains moisture and sound resisting properties; and which is provided with a surface of wire-mesh in order to receive a coat of plaster after partition erection.

15 Other and further objects reside in the provision of general details of construction and arrangement and combination of parts hereinafter to be set forth in full.

With these and still other objects in view 20 the invention consists of the novel construction hereinafter described and finally claimed.

The nature, characteristic features and scope of the invention will be more fully 25 understood from the following description taken in connection with the accompanying drawings forming part hereof, and in which:

Fig. 1, is a fragmentary view, in perspective, of a slab for partition erection embodying the invention.

Fig. 2, is a fragmentary view in vertical elevation of one way of slab erection and also showing a coat of plaster applied.

Fig. 3, is a fragmentary view, partly in elevation and partly in vertical section of another mode of slab erection; and

Fig. 4, is a fragmentary view in front elevation of Fig. 3, with the slab secured to place.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise ar-

rangement and organization of the instrumentalities as herein shown and described.

Referring now to the drawings in detail, and with especial relation at this time to Fig. 1, the reference numeral 1 designates a sheet of card board, paper or the like one face of which has applied thereto as by glue a second sheet 2 of the type or character usually termed "corrugated" which corrugations lend stiffness and stability to the product as is well known in the art. For the purposes of the present invention I treat said sheets 1 and 2 with fireproofing material of any suitable or desired formula as occasion may require. To one face, preferably and in practice to the corrugated sheet 2, I apply wire mesh 3 and secure the same to said sheets 1 and 2 by means of staples 4 or equivalent securing mediums. To the opposite face of the paper or card-board, that is the smooth face, I apply a sheet of felt 5, preferably of the type known commercially as "insulating felt" because of its temperature and fire resisting properties. Such sheet of felt I prefer to attach to the paper or card-board by means of glue. The article so produced is slablike; may be made in any desired size at a plant and shipped for erection; is cheap, light, strong, durable and efficient, and may be easily handled.

As shown in Fig. 2, the partition structure above described may be secured to a wooden support, as for example a vertical beam 6 by means of nails 7. Obviously the support may be horizontally arranged as when a ceiling is being erected. With the slab in fixed position a coat of plaster 8 is applied to the wire-mesh 3.

In Figs. 3 and 4 I have shown one method of erection of said slab where metal beams or girders are used. In said figures the reference numeral 9 designates a metal beam having arranged thereon a clip of metal, preferably stamped from a blank and having beam engaging portions 10-11. The clip is provided with a substantially arrow-shaped head 12 for slab penetration, which head 12 is oppositely notched at 13. When the slab is pierced by the arrow shaped head, accomplished by puncture of said felt and paper,

as is readily apparent, the head 12 is bent over as clearly seen in Fig. 4 to secure the slab in place. However, in order to assist in the attachment I employ a short piece of wire 14 which is caused to engage around said head 12 and within the notches 13 before the head is bent over upon the wire-mesh.

Obviously the number of supports employed, the size of the slabs, the number of staples, nails or slab penetrating points depends entirely upon the work being done and the views in the drawings are fragmentary and merely for illustrative purposes. The above described slab comprises a new article of manufacture capable of manufacture at a central plant for shipment to place of erection in standard or special sizes as required.

It will now be apparent that I have devised a novel and useful construction which embodies the features of advantage enumerated as desirable in the statement of the invention and the above description and while I have in the present instance shown and described the preferred embodiments thereof which have been found in practice to give satisfactory and reliable results, it is to be understood that the same are susceptible of modification in various particulars without departing from the spirit or scope of the invention or sacrificing any of its advantages.

What I claim is:

As a new article of manufacture, a combined key and insulator for plastering purposes comprising a sheet of cardboard having inner and outer plane surfaces, said cardboard being treated with fire proofing material, a sheet of insulating material possessing temperature and fire resisting properties adhesively secured to the inner face of said cardboard, a sheet of corrugated paper treated with fire resisting material covering the outer face of said cardboard, a piece of wire mesh covering the exposed face of said corrugated paper, and staples for attaching said wire mesh with respect to the aforesaid elements in a manner to present a unit flexible enough to be manufactured at a central plant and shipped therefrom in roll form as a unitary structure for instant erection by a single group of mechanics, the points of said staples penetrating said corrugated paper and cardboard and entering said insulating material.

In testimony whereof, I have hereunto signed my name.

FREDERICK M. VENZIE.
